UNITED STATES PATENT OFFICE.

MARIUS C. A. LATOUR, OF PARIS, FRANCE, ASSIGNOR TO LATOUR CORPORATION, OF JERSEY CITY, NEW JERSEY, A CORPORATION OF DELAWARE.

THERMIONIC AMPLIFYING APPARATUS.

Application filed November 2, 1918, Serial No. 260,909, and in France December 20, 1918.

(GRANTED UNDER THE PROVISIONS OF THE ACT OF MARCH 3, 1921, 41 STAT. L., 1313.)

The object of the invention is to provide thermionic tube amplifiers constructed in the manner set forth in my Patent No. 1,405,523, granted February 7, 1922, and particularly suitable for the purpose of amplifying current of a specified frequency.

Such amplifiers are advantageous when it is desired to suppress currents of atmospheric origin in wireless receivers, or else 10 when it is desired to amplify a reception of specified pitch.

In accordance with a theory commonly admitted, atmospheric currents are mainly due to excitations by shock of the receiving 15 antenna, giving rise to oscillations having the natural period of the antenna; and consequently having in the ordinary methods of reception the very period of the oscillations that are being received. According 20 to the invention, the period of the oscillations due to the currents of atmospheric origin may be differentiated from the period of the oscillations that it is desired to receive by tuning the antenna circuit to a frequency 25 different from that of the oscillations to be received, and subsequently reinforcing by means of one or more thermionic tubes the reception thus weakened, without reinforcing the interfering oscillations.

30 This result is arrived at by utilizing in the thermionic tube amplifiers high frequency iron-cored transformers as proposed in my above mentioned patent and by constructing them in such a way that they take a large magnetizing current (few actual turns with an air gap or a multiplicity of air gaps in the magnetic circuit to increase the reluctance thereof) at the frequency corresponding to the wave length in question, and by 35 branching across their terminals a capacity, which at this frequency absorbs a leading wattless current equal to the lagging magnetizing current of the transformer.

40 There is thus obtained the condition of resonance which gives the maximum amplification for the given frequency. Since the condition of resonance does not exist for all other wave lengths, the received currents corresponding to the latter are not 45 amplified to the same extent.

50 What has just been said is also applicable to low-frequency amplification when it is desired to amplify received currents of musical

note frequency. It is accordingly possible, by arranging suitable capacities at the 55 terminals of the primaries or secondaries of the low frequency transformers (constructed to absorb a large magnetizing current) to amplify more particularly received currents of musical note frequency. 60

In a high and low frequency amplifier, therefore, it is possible to provide for the selection by wave length on the high-frequency amplification, and for selection by musical note frequency on the low-frequency 65 amplification.

In the accompanying drawings:

Figure 1 shows a type of the magnetic circuit of the transformer.

Figure 2 gives a diagram of an amplifier 70 for high-frequency current.

Figure 3 is a diagram of an amplifier for low-frequency current.

Fig. 1 shows by way of example one of the forms that might be adopted for the 75 transformer. As described in my Patent No. 1,405,523, the primary winding may consist of a coil Y sandwiched between the coils X and Z which are connected in series and constitute the secondary winding, or 80 conversely X and Z may be the primary and Y the secondary. This arrangement greatly reduces magnetic leakage between the primary and secondary, or, in other words, gives close electromagnetic coupling. 85 In accordance with the present invention the magnetic circuit is made to include an adjustable gap or a plurality of gaps occupied by air or other non-magnetic material. In Fig. 1, reference character E 90 represents by way of example three such air gaps.

Figure 2 shows an amplifier with four thermionic tubes, 1, 2, 3, 4. Each of these thermionic tubes comprises a plate, a grid 95 and a filament. The filaments are heated by the common battery 5. The required potential difference between the filaments and the plate is supplied by the battery 6.

The antenna current which it is desired 100 to amplify is led to the terminals 13 and 14 and is amplified by the tubes 1, 2, 3, and 4 successively, to which it is led through the air-gap transformers 7, 8 and 9. Upon the secondaries of these transformers capacities 105 15, 16 and 17 are utilized, which are ad-

justed so that each of the circuits may be tuned to the wave length that is to be amplified.

Finally the last tube 4 detects the current, due to the capacity 11 shunted by a resistance inserted in series with its grid, and the received current reaches the receiver 10 placed on the secondary of a telephone transformer 12.

10 Figure 3 shows the amplification of a current of low frequency, and consequently possessing a specified musical pitch. In this figure the same letters represent the same elements as in Figure 2 and the telephone transformer is also tuned.

The low-frequency current, instead of arriving directly between the grid and the filament of the first tube, is led thereto through the transformer 7.

20 As in the case of Figure 2, capacities 15, 16 and 17 are provided, but they are tuned to the frequency of the current or specified periodicity to be reinforced.

What I claim as new, and desire to secure 25 by Letters Patent of the United States, is:

1. Amplifying apparatus for radio and the like signals, comprising a thermionic tube containing filament, grid and plate members, and a magnetic-cored transformer 30 with a plurality of air gaps in its magnetic circuit to increase the reluctance thereof, said transformer having its primary winding adapted to receive the current to be amplified and its secondary winding connected to the grid circuit of the thermionic tube, said transformer being adapted, by capacity adjunction, to form a resonant unit for a specified frequency.

2. Amplifying apparatus for radio and 40 the like signals, comprising a thermionic tube containing filament, grid and plate members, and a magnetic-cored transformer with an air gap in its magnetic circuit to increase the reluctance thereof, said transformer having its primary winding adapted to receive the current to be amplified and its secondary winding connected to the grid circuit of the thermionic tube, said transformer being adapted, by capacity adjunction, to form a resonant unit for a specified frequency.

3. Amplifying apparatus for radio and 45 the like signals, comprising a thermionic tube containing filament, grid and plate

50 members and a magnetic-cored transformer with a variable air gap in its magnetic circuit to vary the reluctance thereof, said transformer having its primary winding adapted to receive the current to be amplified

55 and its secondary winding connected to the grid circuit of the thermionic tube, said transformer being adapted, by capacity adjunction, to form a resonant unit for a specified frequency.

60 4. In a thermionic amplifier for radio-

telegraphic and similar signals, the combination with a wave collecting circuit tuned to a frequency slightly different from that of the oscillations to be amplified, of a magnetic-cored transformer with a plurality of air gaps in its magnetic circuit, to increase the reluctance thereof, having its primary winding adapted to receive the current to be amplified and its secondary winding connected to the grid circuit of a thermionic tube, said transformer being adapted, by capacity adjunction, to form a resonant unit for the frequency of the current to be amplified.

5. In a thermionic amplifier for radio-telegraphic and similar signals, the combination with a wave collecting circuit tuned to a frequency slightly different from that of the oscillations to be amplified, of a magnetic-cored transformer with an air gap in its magnetic circuit to increase the reluctance thereof, having its primary winding adapted to receive the current to be amplified and its secondary winding connected to the grid circuit of a thermionic tube, said transformer being adapted, by capacity adjunction, to form a resonant unit for the frequency of the current to be amplified.

6. In a thermionic, amplifier for radio-telegraphic and similar signals, the combination with a wave collecting circuit tuned to a frequency slightly different from that of the oscillations to be amplified, of a magnetic-cored transformer, comprising an air gap, said air gap being variable so as to permit of tuning in accordance with the oscillations to be amplified, and an amplifying tube the grid circuit of which is connected to the said magnetic-cored transformer.

7. Apparatus for radio and like signals, comprising a plurality of thermionic tubes each containing filament, grid and plate electrodes, circuits including said electrodes, a high-frequency transformer coupling the circuits of adjacent thermionic tubes in cascade, said transformer comprising separate primary and secondary windings, the circuits of said windings being closely coupled electromagnetically, and a capacity connected across at least one of said windings to compensate for the magnetizing current of the transformer, whereby said transformer as a whole and said capacity constitute a single resonant unit.

8. Amplifying apparatus for radio and like signals, comprising a plurality of thermionic tubes each containing filament, grid and plate electrodes, circuits including said electrodes, a high-frequency transformer coupling circuits of said thermionic tubes in cascade, said transformer comprising separate primary and secondary windings together with a core of magnetic material, the circuits of said windings being closely coupled electromagnetically, and a capacity con-

5 nected across at least one of said windings to compensate for the magnetizing current of the transformer, whereby said transformer as a whole and said capacity constitute a single resonant unit.

9. Amplifying apparatus for radio and like signals, comprising a plurality of thermionic tubes each having filament, plate and grid electrodes, circuits including said 10 electrodes, a high-frequency transformer coupling circuits of adjacent thermionic tubes in cascade, said transformer comprising separate primary and secondary windings, the circuits of said windings being 15 closely coupled electromagnetically, and a capacity connected across at least one of said windings and arranged to constitute a single resonant unit with said transformer as a whole.

20 10. Amplifying apparatus for radio and like signals, comprising a plurality of thermionic tubes each having filament, plate and grid electrodes, circuits including said electrodes, a high-frequency transformer coupling circuits of adjacent thermionic tubes in 25 cascade, said transformer comprising separate primary and secondary windings together with a core of magnetic material, the circuits of said windings being closely coupled electromagnetically, and a capacity con-

nected across at least one of said windings and arranged to constitute a single resonant unit with said transformer as a whole.

11. Amplifying apparatus for radio and like signals, comprising a plurality of thermionic tubes each having filament, plate and grid electrodes, circuits including said electrodes, a high-frequency transformer coupling circuits of adjacent thermionic tubes in cascade, said transformer comprising separate primary and secondary windings, the circuits of said windings being closely coupled electromagnetically, a capacity connected across at least one of said windings and arranged to constitute a single resonant unit with said transformer as a whole, and adjustable means for tuning said resonant unit to the frequency of the current to be amplified.

12. In a signaling system, a detecting device for changing the frequency of an incoming signal, a plurality of amplifying devices coupled to said detecting device by resonant units, each unit including a magnetic-cored transformer having an air gap, and a capacity across each transformer whereby each unit is resonant to a specified frequency.

In testimony whereof I affix my signature.
MARIUS C. A. LATOUR.
